ROAD PAVING MACHINE

Enoch Berg Jorgensen, Los Angeles, Calif., assignor, by mesne assignments, to Viber Company, Los Angeles, Calif., a corporation of California

Continuation of application Serial No. 19,055, April 30, 1935. This application August 9, 1937, Serial No. 158,150

7 Claims. (Cl. 94—48)

This invention relates to paving machines, and in particular to machines for laying plastic materials such as concrete upon a prepared roadway. This application is a continuation of my co-pending application Serial No. 19,055, filed April 30, 1935. The objects of my invention are to provide a machine which levels off and compacts a mass of concrete or other plastic materials placed upon the roadway; to provide a machine which vibrates the concrete and other plastic materials in place on the roadbed; to provide a machine which gives a compact and finished pavement; to provide a machine with means for vibrating the plastic material on a roadbed between crosswise expansion joints, and with means for raising and lowering the vibrating mechanism over these joint members; to provide a method for placing and finishing a plastic mass as a paving. These and other objects will be apparent from the following description and the drawings in which

Fig. 1 is a side section taken at 1—1 of Fig. 4, of one form of my paving machine;

Fig. 2 is a partial side section taken at 2—2 of Fig. 3, of a portion of my machine showing the vibrators in a partly withdrawn position.

Fig. 3 is a forward end elevation of the machine, with the vibrators in position indicated in Fig. 2, and with parts and portions broken away to facilitate illustration;

Fig. 4 is a plan view of the paving machine, with parts and portions removed to facilitate illustration.

My paving machine, in one form, consists of a carriage having side members 11, cross members 12, 13, 14, and 15, wheels 16 adapted to travel on headers or side boards 17 forming the side margins of the roadway. The wheels 16 are supported in bearings 18 by shafts 19. Vibrators 20 connected by flexible drive shafts 21 to rotary means 22 are mounted by clips 30 upon support members 23 which are attached to the shaft 24, which is adapted to be rotated in the bearings 41 mounted on the side members 11. A worm 25 on a shaft 26 rotatably held in brackets 27 and having a handwheel 28 operates through the worm gear 29 to raise and lower the support members 23, and the vibrators 20 attached thereto. Longitudinal support members 31 for the raising and lowering means are attached to the carriage cross members 13 and 14. A strike-off bar 32 whose vertical position is adjustable by means of slots 33 and bolts and nuts 34, is attached to the underside of the carriage frame by bracket means 35, with angle braces 36 to the cross-member 14. Attached by chains 37 to the bracket means 35,

which holds the strike-off bar 32 in rigid position relative to the carriage frame, is a finishing plate 38 which is free to be moved over the top surface of the paving material. In the following description and claims, concrete is specifically referred to, but the machine may be used in working any other suitable plastic materials which may be employed for paving, including black or asphaltic mixtures and the like.

My machine is preferably used along a roadway which has been graded and prepared for paving by providing headers 17 for the margins of the pavement. It is also usually the practice to insert at intervals, cross-members, indicated at 40, which may be lumber, or may be pre-formed expansion joint members, made of composition materials. The wheels 16 of the carriage of my machine are designed to roll on the headers 17, although other traction means may be employed. The carriage may be propelled along the highway by any suitable means, such as a motor mounted on the carriage to drive the wheels 16 or the machine may be attached to other equipment used similarly over the roadway, or by tractors at the side of the roadway. Also there may be assembled on the carriage of my machine a gas propelled engine to drive the vibrators directly through flexible drive shafts, or a gas propelled motor for driving air compressors to furnish compressed air for air motors attached to the vibrators 20, or for driving a generator to supply electrical energy for the vibrator motors 22 if electric motors. This auxiliary equipment may be selected to suit the conditions applying where the road is being paved.

The structure of my machine may be varied in detail, the arrangement shown being simple and designed to illustrate the principles, and to show one embodiment of my invention. Four similar vibrator units 20 are shown but any number may be used, as required, to set the concrete in suitable vibration across the full width of the paving strip or slab. It has been well demonstrated heretofore that high frequency vibration of unset concrete mixes causes the material to flow and be compacted into a designated space, giving a denser and stronger finished concrete. The vibrators may be of any suitable mechanism which will produce high frequency vibrations in the concrete; an eccentric weight mounted upon a shaft within a protecting shell being a preferred form. Such a vibrator is shown in my co-pending patent application Serial No. 7,927 dated February 23, 1935, issued as Patent No. 2,018,789 October 29, 1935. By the use of vibration fre-

quencies of 4,000 to 10,000 per minute, it has been found that quite dry mixes may be compacted upon the roadbed by pulling through the distributed mixtures, vibrators of the above type. In 5 operation, the rapidly vibrating vibrators 20 are lowered into the concrete mixture which has been previously distributed roughly over the desired area between the headers 17, by rotating the hand-wheel 28, which operates through the worm 10 gearing 24-25 to revolve downwardly the supporting frame 23. The vibrators 20, being vibrated rapidly by the rotation of the motors 22 through the flexible drive shafts 21 quickly dig their free ends into the moist loose concrete. 15 Simultaneously the paving machine is moved forward along the roadway and the vibrator tubes 20 take the position inclined downwardly and rearwardly as indicated in Fig. 1, and are pulled in this position through the concrete. This inclined position of the vibrator has been found to be important in producing a compact mass of concrete, and in closing up the furrow made by the vibrator as it passes through the mass. It 20 has also been found that by using the vibrator tube in this inclined position that any air trapped in the concrete, which would cause voids, passes up around the inclined tube, thus allowing the concrete immediately above the lower tip of the vibrator tube to be compacted from the bottom 25 to the top of the layer.

While the use of my machine requires that the concrete mass be distributed fairly evenly over the roadbed ahead of the machine, to overcome the disturbance of levels caused by pulling the 30 vibrators through the concrete, and to provide for the final leveling of the top surface after compaction, a strike-off bar 32 is placed above the vibrators 20 in their lower position. It has been found that since the vibrators 20 cause the 35 mass of concrete in the immediate surroundings to vibrate, that this strike-off bar 32 will function best if rigidly attached to the carriage frame. Its vertical position is made adjustable to suit the particular operating conditions. As pointed 40 out, as the concrete is vibrated, some of the "cement paste", that is some fines including cement with water comes to the surface, following particularly the path of the inclined vibrator tubes. The strike-off bar 32 levels off the concrete, particularly this fine material which floats to the 45 top, and the final road finish is produced by the finishing plate 38, which is attached behind the strike-off bar 32 and directly above the lower end of the partly submerged inclined vibrator tube 20, in its lower position. I have discovered 50 that a sheet metal plate 38, preferably curved with the convex surface forming the contact on the surface of the concrete, and without weighting, and attached for loosely dragging over the 55 surface, gives a satisfactory road surface finish. The concrete under the finishing plate 38 is in vibrating condition from the action of the vibrators 20. Vibrations are transmitted to the plate 38, and this floating plate under its own 60 weight brings the proper amount of fine material and water to the surface to insure the correct surface compaction and smoothing.

To avoid or skip the cross-partitions or expansion joints which are used in long stretches 65 of pavement, the vibrators 20, as they approach these cross members 40 are gradually raised to a vertical position as indicated in Fig. 2. The vibrators are then lifted out of the concrete by the further rotation of the support 23, thus vibrat- 70 ing all of the concrete up to the joint and

up to the top surface where the vibrator leaves the concrete.

As the whole machine is moved forward, the vibrators 20 are re-inserted in the concrete (to the left of 40 in Fig. 2) and the vibrators again 5 take the inclined positions as shown in Fig. 1 as the machine moves still farther forward. The vibrators 20 must be kept operating, that is vibrating, during the insertion, passage through, and withdrawal from the concrete mass on the 10 roadbed.

In the preferred arrangement of parts, as shown and above described, electric motors drive the eccentrically weighted shafts in the vibrators 20, through the flexible drive shafts 21; and in 15 each unit the motor and vibrator are so placed as to more or less counter-balance each other on the supporting members 23. The vibrators 20 may be operated in any suitable manner, by 20 electric motors, or air motors, and they may be attached as shown, or coupled close to the vibrating tubes 20. The arrangement shown provides the necessary flexible vibration-dampening 25 connection between the motor and the vibrator itself, and the support 23, so that the whole machine is not vibrated, and thus increasing the available vibrational energy which may be transmitted directly to the concrete. The vibrator units 20 may be so constructed as to contain the motive power and the eccentric weight as 30 an integral vibrating mechanism.

The method of operation consists in vibrating the spread-out concrete mass by pulling through it partly submerged vibrating elements, hereby causing the unset concrete in proximity with the vibrators to be set in vibration, and simultaneously striking off the top surface by means of a rigid strike-off bar, and smoothing and slicking over the fine mixture of sand, cement and water which rises to the surface during vibration, by dragging a finishing plate over the surface immediately after the vibration, and while the mass is still vibrating.

While I have illustrated my invention by one preferred embodiment, I do not wish to be limited by this particular arrangement of parts, but desire to include within the scope of my invention the combinations and arrangements substantially as set forth in the following claims.

I claim:

1. In a road paving machine adapted to travel along a prepared roadway upon which has been placed an unset and uncompacted concrete mixture, vibratory means attached to said carriage and adapted to be moved through the concrete, a crosswise top-leveling strike-off bar rigidly attached to the carriage of said machine and adapted to roughly level off the top surface of the vibrating concrete mixture between said vibratory means and said strike-off bar, an unsupported surface-finishing plate adapted to float on the top surface of the concrete and to be dragged over the concrete surface behind the strike-off bar at a position substantially directly over the lower end of the vibratory means.

2. In a road paving machine adapted to travel along a prepared roadway upon which has been distributed an unset and uncompacted concrete mixture, partly submergible tubular vibratory means inclined downwardly and rearwardly relative to the forward end of the machine and adapted to be moved in this position through the unset concrete with the forward movement of the machine, a crosswise top-leveling strike-off bar rigidly attached to the carriage of said ma- 75

chine at a position rearwardly of the top surface end of said vibratory means, and a surface-finishing plate adapted to be dragged over the vibrating portion of the concrete at a position substantially above the lower end of the vibratory means and rearwardly of the strike-off bar.

5. In a road paving machine, a carriage adapted to travel along a roadway upon which has been distributed an unset concrete mixture, insertible vibrators connected by flexible shafts to rotary means, supporting means for said vibrators adapted to hold said vibrators in a rearwardly inclined position in said concrete mixture during vibration and forward movement of the carriage and also adapted by rotation to withdraw and insert the vibrators in the concrete, means for rotating said support, a finishing plate positioned on the concrete surface above said inclined vibrators in their fully inserted position and adapted to be dragged by the carriage over the surface of a vibrating portion of the concrete.

4. In a road paving machine, a carriage adapted to travel along a roadway upon which has been distributed an unset concrete mixture, insertible vibrators, actuating means for said vibrators, supporting means for said vibrators and actuating means attached to said carriage and adapted to hold the vibrators within the concrete mixture during vibration and forward movement of the carriage and to withdraw or insert the vibrators in the concrete, means for rotating said support, a strike-off bar attached to the carriage across the roadway and rearwardly of the point of insertion of the vibrators, and a finishing plate positioned rearwardly of the strike-off bar and adapted to be dragged by the carriage over a vibrated portion of the concrete.

5. In a road machine, a carriage adapted to travel along a prepared roadway upon which has been distributed an unset and uncompacted concrete mixture, partly submergible tubular vibrators inclined downwardly and rearwardly relative to the forward end of the machine and adapted to be moved in this position through the unset concrete, means for actuating said vibrators, supporting means for said vibrators and actuating means adapted to move in a circular path perpendicular to the roadway surface, the vibrators being disposed tangentially to this circular path so that at the lower end of the path the vibrators are in inclined position within the concrete and at the upper end of which path the lowest portions of the vibrators are entirely out of and above the roadway, means for moving the support through said circular path, a crosswise top-leveling strike-off bar rigidly attached to said carriage at a position rearwardly of the points of entry

of said vibrators into the concrete, and a surface finishing plate extending transversely between the margins of said roadway adapted to be dragged over the vibrated concrete at a position substantially directly above the lower end of the vibratory means and rearwardly of the strike-off bar.

6. In a road paving machine adapted to travel along a prepared roadway upon which has been distributed an unset concrete mixture, a carriage, a plurality of encased rotary vibratory mechanisms, means attached to said carriage for raising and lowering said vibratory mechanisms into and out of the unset concrete, attaching means for said encased vibratory mechanisms to said raising and lowering means including a non-rigid connection between said encased mechanism and said means for raising and lowering adapted to prevent the vibration of said raising and lowering means, rotary means for actuating said vibratory mechanisms, a crosswise strike-off bar rigidly attached to the carriage of said machine and adapted to roughly level off the top surface of the vibrating concrete mixture between said vibratory means and said strike-off bar, and a surface finishing plate extending transversely between the margins of said roadway adapted to be dragged over the vibrating concrete at a position substantially directly above the lower end of the vibratory means and rearwardly of the strike-off bar.

7. In a road paving machine adapted to travel along a prepared roadway upon which has been distributed an unset concrete mixture, a carriage, a plurality of encased rotary vibratory mechanisms, lever means attached to said carriage for inserting and withdrawing said vibratory mechanisms into and out of the unset concrete and for holding said vibratory mechanisms in inclined position downwardly and rearwardly of the front of the machine, attaching means for said vibratory mechanisms to said lever means including a non-rigid connection between said encased mechanism and said lever means adapted to prevent the vibration of said lever means, rotary means for actuating said vibratory mechanisms, a crosswise strike-off bar rigidly attached to the carriage of said machine and adapted to roughly level off the top surface of the vibrating concrete mixture between said vibratory means and said strike-off bar, and surface finishing plate extending transversely between the margins of said roadway adapted to be dragged over the vibrating concrete at a position substantially directly above the lower end of the vibratory means and rearwardly of the strike-off bar.

ENOCH BERG JORGENSEN.
